UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

LAMP.

SPECIFICATION forming part of Letters Patent No. 642,528, dated January 30, 1900.

Application filed September 2, 1899. Serial No. 729,307. (No model.)

To all whom it may concern:

Be it known that I, FRANK RHIND, a citizen of the United States, residing at Bridgeport, Connecticut, have invented a new and useful Improvement in Lamps, of which the following is a specification.

My invention relates, chiefly, to lanterns such as are used on cycles or other vehicles for the consumption of acetylene or other gas.

10 It is intended to render such lamps at once more simple and more efficient.

In the accompanying drawings, Figure I is a side elevation, partly broken away, of a cycle-lamp embodying my invention. Figs. II 15 and III are similar views showing modifications. Fig. IV is a top view of a lamp, showing another part of my invention.

1 Designates a lamp-body; 2, a gas-tube; 3, a burner; 4, a reflector, which may be provided with recess 41; 5, a wind-guard having central aperture 51 and perforations 52; 20 Fig. IV, a valve; 7, a jam-nut.

In the example of my invention illustrated in Fig. I of the drawings the lamp-body 1 may be of any desired form. The upper end of the gas-tube 2 is formed to carry a horizontally-disposed burner 3. A reflector 4 (shown as a segment of a sphere) is also mounted upon the end of the gas-tube 2. Within 25 the reflector 4 and surrounding the burner-tip 3 is a wind-guard 5, having an axial aperture 51 and lateral perforations 52.

The operation of my device will be readily understood from an inspection of the drawings. It is clear that gas generated in the body 1 and passing out through the burner-tip 3 may be lighted and that the light will be thrown forward by the concave reflector 4. It has been found by experiment with 30 lamps of this general type that a wind "on the beam"—i. e., one inclined, say, forty to fifty degrees from a head-wind—will frequently extinguish the flame. I therefore provide a wind-guard, shown as a thimble 5, having an axial aperture 51 for the passage of the flame and lateral perforations 52 for the admission of air. This wind-guard is 35 preferably made to screw onto the end of the gas-tube 2 and may serve, in connection with the jam-nut 7, to hold the reflector 4 in position. I have found in practice that this thimble

serves to protect the flame from extinguishment even in a very strong wind.

In Fig. II of the drawings I have shown the reflector 4 as of frusto-conical shape and as 55 having a rearward extension 41, of reduced diameter, in which the thimble 5 is placed. This shape is advantageous as lessening the possibility of accident from the flame projecting beyond the open mouth of the reflector and as concentrating the light upon a longer narrower path.

In Fig. III the wind-guard 5 is shown as consisting of a part of the rear wall of the reflector 4, perforate at 51 and 52, as shown, 65 and of the side walls of a rearward extension or recess 41, which is in this case formed of a separate piece of metal and secured, as by riveting, to the reflector 4. It is obvious that the operation of the device is not hereby 70 changed.

The object of the present invention is to increase the relative efficiency of the lamp by substituting a small single-tip burner for the large double-tip burners used in the better 75 grade of acetylene cycle-lamps and projecting a greater percentage of the light upon the road. To further increase this efficiency, I provide the two reflectors 4 and burners 3. (Shown in Fig. IV of the drawings.) In operation 80 one of these burners may be used in fairly-lighted streets or roads and both when a greater illumination is required. For this reason I provide one of the branches of the gas-tube 2 with a valve or cock 7. 85

I have filed an application for patent concurrent with this in which is shown a reflector provided with a rearwardly-extending recess or portion of reduced diameter. It is clear that I do not herein claim such a reflector except in combination with a wind-guard, as specified. I have also filed an application concurrent with this in which is shown a horizontally-disposed gas-burner near the rear end of an open reflector and a wind-guard 90 consisting of a strip of perforate metal or its equivalent at the free or open end of the reflector.

My present invention relates, so far as the protection of the flame from the wind is concerned, to such an arrangement only as provides an open concave reflector, a burner-tip

at the rear end of said reflector whose axis is substantially coincident or at least parallel with that of the reflector, and a wind-guard within said reflector covering or protecting the root of the flame emitted from said burner-tip, said wind-guard being reduced in diameter at its free end or provided with an exit-aperture for the flame substantially smaller than the inner diameter of the body of said guard.

I do not consider myself limited to the particular forms of my device shown, as many mechanical alterations may be made therein without departing from my invention.

15 What I claim is—

1. In combination an open concave reflector whose axis is substantially horizontal, a gas-burner tip at or near the rear end of said reflector the axis of said tip being also substantially horizontal and a wind-guard within said reflector and adapted to protect the root of the flame issuing from said burner-tip, the exit-aperture for the flame through said guard being of substantially less diameter than the body portion of said guard, substantially as described.

2. In combination an open concave reflector, a gas-burner tip at or near the rear end of said reflector and whose axis is substantially coincident with that of said reflector and a wind-guard within said reflector and adapted to protect the root of the flame issuing from said burner-tip, the exit-aperture for the flame through said guard being of substantially less diameter than the body portion of said guard, substantially as described.

3. In combination an open concave reflector, a gas-burner tip at or near the rear end of said reflector and adapted to project a flame substantially in the axis thereof and a wind-guard within said reflector and adapted to protect the root of such flame, the exit-aperture for the flame through said guard being of substantially less diameter than the body portion of said guard, substantially as described.

4. In combination an open concave reflector, a gas-burner tip at or near the rear end of said reflector and adapted to project a flame substantially in the axis thereof, and a wind-guard within said reflector surrounding and covering said burner-tip and reduced in diameter at its free end so that the exit-aperture for such flame is of substantially less diameter than the body of said wind-guard, substantially as described.

5. In combination an open concave reflector, a gas-burner tip at or near the rear end of

said reflector and adapted to project a flame substantially in the axis thereof and a wind-guard within said reflector surrounding and covering said burner-tip perforated for the admission of air and having at its free end an exit-aperture for the flame of a diameter less than that of the body of said wind-guard, substantially as described.

6. In combination an open concave reflector, a gas-burner tip at or near the rear end of said reflector and adapted to project a flame substantially in the axis thereof and a dome-shaped wind-guard within said reflector surrounding said burner-tip and provided with a plurality of perforations through its side walls for the admission of air and an axial exit-aperture in its free end for the flame, substantially as described.

7. In combination an open concave reflector, a gas-burner tip at or near the rear end of said reflector and adapted to project a flame substantially in the axis thereof and a detachable wind-guard within said reflector and adapted to protect the root of such flame, the exit-aperture for the flame through said guard being of substantially less diameter than the body portion of said guard, substantially as described.

8. In combination an open concave reflector provided with a rearwardly-extending recess or portion of reduced diameter, a gas-burner tip within said recess the axis of said burner and of said recess being substantially coincident and a wind-guard within said reflector and adapted to protect the root of the flame issuing from said burner-tip, substantially as described.

9. In combination a lamp-body, a plurality of burner-tips operatively connected with said body and a plurality of reflector portions each inclosing one of said burner-tips, the axes of said reflectors being substantially parallel so as throw the emitted light from both flames in substantially the same direction.

10. In combination a lamp-body, a plurality of gas-burner tips operatively connected with said body, a plurality of reflector portions each inclosing one of said burner-tips and means for cutting off the supply of gas from one of said tips, the axes of said reflectors being substantially parallel so as throw the emitted light from both flames in substantially the same direction.

FRANK RHIND.
